CLAIM

The ornamental design for a cutting insert, as shown and described.

DESCRIPTION

FIG. 1 is a perspective view of a cutting insert showing my new design. The mesh lines indicate that: (a) there is a gold colored band which extends around the cutting insert along the cutting insert's side walls; (b) in the vertical direction, the gold colored band extends upwards from the base of the cutting insert; and (c) gold color is also present on the through bore walls of the cutting insert. The remaining surfaces of the cutting insert are black.

FIG. 2 is a first side view of a cutting insert, the other side views being the same; and,

FIG. 3 is a top view of a cutting insert, the bottom view being a mirror image of the top view.
